UNITED STATES PATENT OFFICE.

WILLIAM PRELLWITZ, OF EASTON, PENNSYLVANIA, ASSIGNOR TO INGERSOLL-RAND COMPANY, OF JERSEY CITY, NEW JERSEY, A CORPORATION OF NEW JERSEY.

PLATE-VALVE.

1,352,025.

Specification of Letters Patent.

Patented Sept. 7, 1920.

Application filed April 2, 1920. Serial No. 370,741.

To all whom it may concern:

Be it known that I, WILLIAM PRELLWITZ, a citizen of the United States, residing at Easton, in the county of Northampton and State of Pennsylvania, have invented a certain new and useful Improvement in Plate-Valves, of which the following is a specification.

This invention relates to plate valves for blowing engines, pumps, compressors and the like, but more particularly to a valve in which the valve plate is in the form of a thin strip of sheet metal. In a valve of this type the valve seat is usually provided with a plurality of passage ways over which the valve plates are adapted to seat, and a guard or stop plate forms a stop for limiting the lift of the valve plates. Springs may be provided between the guard and valve plates for returning and seating the valve plates and in the usual constructions difficulty is experienced in assembling the parts and adjusting the springs over the valve plates, because the springs are ordinarily guided in sockets or recesses within the guard or stop plate.

The primary object of the present invention is to secure a simple and convenient construction by means of which the springs may be inserted in or removed from the spring holding sockets or apertures in the guard from the outside after the valve seat, valve plate or plates and guard have been assembled, without disturbing the adjustment of the parts already assembled. Such a construction is a material advantage in a valve of this type, particularly in those cases in which a plurality of valve plates are used because it is obviously difficult to first arrange the valve plates on their seats, and then adjust the springs in the guard, and finally assemble the parts in proper position and alinement.

In accordance with my improved and simplified construction, the valve seat, valve plate or plates and guard or stop are first assembled as desired, and then one or more springs are placed in position in the guard over the valve plate or plates and any suitable device or means, as a guard plate, is adapted to be removably secured to the guard for holding the springs in position.

Another advantage of this construction of valve plates and springs resides in the fact that parallel motion of the valve plates be-

tween the seat and guard is more certainly secured and maintained since the springs are more readily accessible and may be conveniently changed or adjusted as desired.

The invention is illustrated in several of its preferred forms in the accompanying drawings in which—

Fig. 1 is a sectional side elevation of one form of valve having one spring for each valve plate,

Fig. 2 is a perspective view partly in section of the valve seat shown in Fig. 1 and valve plates adapted to be seated thereon,

Fig. 3 is a perspective view partly in section of the guard shown in Fig. 1 and the springs and spring washers, shown separately, with a supplementary detail top plan view of a portion of the guard indicating the positions of the valve plates with relation to the passages in the guard.

Fig. 4 is a perspective view partly in section of the guard plate shown in Fig. 1,

Fig. 5 is a perspective view partly in section of the cap for the assembled parts of the valve,

Fig. 6 is a sectional side elevation of a modified form of valve having a plurality of springs for the longer valve plates,

Fig. 7 is a perspective view partly in section of the valve seat shown in Fig. 6 and valve plates for the same,

Fig. 8 is a perspective view partly in section of the guard shown in Fig. 6 and the springs and spring washers,

Fig. 9 is a perspective view partly in section of the guard plate shown in Fig. 6,

Fig. 10 is a perspective view partly in section of the cap for the valve shown in Fig. 6,

Fig. 11 is a perspective view of a modified form of guard plate, and

Fig. 12 is a sectional side elevation of a modified form of valve construction.

Referring to the drawings, and at first more particularly to Figs. 1 to 5 inclusive, A represents a valve seat formed in this instance with a plurality of passage ways B over which the valve plates C in the form of narrow flat strips of sheet metal are adapted to be seated. A guard D is mounted on the valve seat over the valve plates C and is provided as shown with the passage ways E in staggered relation to the passage ways B, and the bridges E² adapted to lie over the valve plates C and provided with the end and centrally located recesses F in which

recesses the valve plates are adapted to lift, forming guides for the valve plates, so that the guard also constitutes the guide for the valve plates. The valve plates could also 5 be made straight at their ends and additional intermediate side guides may be provided on the guard shown in Fig. 3 in the positions indicated for the intermediate guides F in Fig. 8.

10 In the construction shown in Figs. 1 to 5 a single spring is provided for each valve plate and in accordance with my construction the central web G of the guard D is formed with apertures H extending entirely 15 through the web from face to face and preferably flared toward the inner recessed portions F of the guard.

In assembling the parts the guard D is preferably placed in an inverted position, 20 the valve plates C are laid in the guide recesses F and the valve seat A is then placed on top and the parts are then turned over. The valve springs J which may be of any suitable form, preferably coiled 25 springs, are adapted to be inserted in the apertures H from the top and they are maintained in position in the apertures by any suitable means as for instance a guard plate K which is secured on the web G of the guard 30 over the springs as by means of the side bolts L passing through the apertures O in the guard plate K and the apertures P in the guard and adapted to be seated in the screw threaded apertures Q in the valve 35 seat A. Any other suitable means may be provided for holding the guard plate in position.

Shoes or washers R are preferably provided for the springs J between the springs 40 and the valve plates C and as shown these shoes or washers R may be inserted through the apertures H in the guard upon the valve plates C and then the springs J placed upon the shoes. These shoes R may be formed 45 with flanges S for centering the springs and the springs are preferably secured to the shoes in any suitable manner. A cap T is preferably provided for the valve when the parts are assembled.

50 If the shoes R were made larger in diameter to afford a larger wearing surface between the same and the valve plates C, or if the springs and shoes are fastened together to form a unit, they may be inserted 55 in the apertures H from underneath before the valve plates C are placed in their guiding slots or recesses F. Means are thus provided in accordance with my construction for applying and maintaining pressure in 60 the springs after the parts have been assembled.

In accordance with this construction the springs J and shoes R may be inserted in or removed from the apertures H in the

guard D after the valve seat, valve plates 65 and guard have been assembled in position. The valve plates C are adapted to lift with parallel motion but if the sheet material from which the valve plates are made is sufficiently thin and flexible, the ends of 70 the valve plates may under certain circumstances lift before the body portion of the strips, as indicated in dotted lines at a in Fig. 1.

In Figs. 6 to 10 inclusive a modified construction is shown in which the guard D is provided with the passage ways E' and also with a plurality of spring receiving apertures H for each of the longer valve plates C. In this instance the guard plate 80 K' is in the form of a disk having the passage ways K² and the webs or bridges K³ adapted to lie over the spring receiving apertures H and maintain the springs in position.

In Fig. 11 a modified form of guard plate 85 U is shown having a body portion V and arms X and Y. The body portion V is adapted to cover the spring receiving apertures H and the arms X and Y are provided with the bolt holes O for the retaining bolts. 90

In Fig. 12 a modified form of valve is shown in which the guard b is provided with screw threaded apertures H' adapted to receive the recessed screw threaded plugs c for holding the springs J in position in the 95 guard. In this instance each individual aperture H' is provided with the spring retaining plug or socket c within which the spring is placed. This construction is advantageous in extremely large valves where 100 the number of springs employed is large and each spring may be inserted separately and in the case of a spring breaking, a new one may be inserted without taking the entire valve apart. 105

I claim—

1. A valve comprising a valve seat, a valve plate adapted to be seated thereon, a guard having an aperture to receive a spring and means for applying and maintaining pressure on the spring after the parts have been assembled. 110

2. A valve comprising a valve seat, a valve plate adapted to be seated thereon, a guard over said valve plate forming a stop, 115 said guard having an aperture open at both faces of the guard and adapted to lie opposite said valve plate, so that a spring may be placed in said aperture after the valve seat, valve plate and guard have been assembled and means for holding said spring in the aperture. 120

3. A valve comprising a valve seat, a valve plate adapted to be seated on said seat, a guard forming a stop for limiting the lift of the valve plate and provided with an aperture passing entirely through the guard from face to face, so that a spring may be 125

placed in said aperture over the valve plate from the outside, and a guard plate for holding said spring in position in the aperture.

5 4. A valve comprising a valve seat, a plate valve in the form of a strip of sheet metal adapted to be seated on said seat, a recessed guard over said valve plate forming a stop, means for inserting a spring 10 through said guard over the valve plate after the valve seat, valve plate and guard have been assembled and means for applying and maintaining compression on the spring after it is placed in position in the 15 guard.

5. A valve comprising a valve seat, a plate valve in the form of a strip of sheet metal adapted to be seated on said seat, a recessed guard over said valve plate forming a stop, an aperture passing through said guard from face to face and open at both ends, affording means for inserting a spring 20 in the aperture over the valve plate after the guard is mounted in position, and a guard 25 plate removably connected to the guard for holding the spring in position and applying compression to said spring.

6. A valve comprising a valve seat, a valve plate adapted to be seated on said seat, a 30 guard mounted over the valve plate, a spring receiving aperture in said guard over said valve plate and means for inserting and removing a spring in said aperture after the

guard is mounted over the valve plate and without removing the guard.

35

7. A valve comprising a valve seat having a plurality of passage ways, plate valves adapted to be seated in the valve seat over said passage ways, a guard mounted on the valve seat over said valve plates, apertures 40 in said guard passing through the same from face to face and adapted to lie opposite the valve plates, springs removably inserted in said apertures from the outside, and a guard plate removably connected to said guard 45 for holding the springs in the apertures over the valve plates and applying compression to said springs.

8. A valve comprising a valve seat having a plurality of passage ways, plate valves in 50 the form of strips of sheet metal adapted to be seated on said seat over the passage ways, a guard mounted on the valve seat over the said plate valves and formed with bridges having guide recesses for the valve plates, 55 said bridges also having apertures passing through from face to face for receiving springs, valve springs adapted to be inserted in said apertures over the valve plates, and a guard plate removably secured to the guard over said apertures for holding the springs in position and applying compression to said springs.

In testimony whereof I have hereunto set my hand.

WILLIAM PRELLWITZ.
